W. W. GRAVES.
RAZOR STROP.
FILED MAR. 31, 1921.

UNITED STATES PATENT OFFICE.

WILLIAM W. GRAVES, OF NORTH DIGHTON, MASSACHUSETTS.

RAZOR STROP.

Application filed March 31, 1921. Serial No. 457,200.

To all whom it may concern:

Be it known that I, WILLIAM WALLACE GRAVES, a citizen of the United States, residing at North Dighton, in the county of 5 Bristol and State of Massachusetts, have invented certain new and useful Improvements in a Razor Strop; and I do hereby declare the following to be a full, clear, and exact description of the invention, such as 10 will enable others skilled in the art to which it appertains to make and use the same.

The object of the invention is to provide a simple and relatively efficient razor strop which is devoid of the objections to which 15 the ordinary leather strop is subject in that it presents a proper stropping and finishing surface initially and without the preparation to which leather straps must be submitted before they can be used effectively 20 and which is adapted to produce a keener and more satisfactory edge than can be produced upon a leather strop or than can be produced upon any strop of other material such as metal heretofore devised or suggested, which is not subject to deterioration 25 by moisture and which can be folded into compact form for storage and transportation without detracting from the efficiency thereof; and with these objects in view the 30 invention consists in a construction of which a preferred embodiment is shown in the accompanying drawings, wherein:

Figure 1 is a perspective view of a strop embodying the invention.

35 Figures 2 and 3 are sectional views of the extremities thereof to show the means for attaching the hanger and handle to permit of removal for rolling the strop into compact form for storage.

40 Figure 4 is an enlarged detail view of a portion of the blade or body portion of the strop.

Figure 5 is a view of the strop folded for transportation.

45 Figure 6 is a sectional view of the folded device.

The strop consists of a flat band of very flexible, highly tempered sheet steel, silver plated throughout and finely scored on one 50 side to provide an edge preparing surface, the opposite side being smooth to form a finishing surface, the band being indicated at 10, the plating of silver or like relatively

soft material being indicated in Figure 2 at 11 and the scoring being shown in the same 55 figure at 12.

While in practice it has been found that the use of silver is advantageous as a coating or plating for the blade or body portion of the strop, it should be noted that the advantage of the use thereof is incident to the fact that such metal is of relatively soft or smooth quality and has an adhesive or frictional effect upon the blade of the razor which is particularly advantageous in drawing the razor blade to a fine edge, but it should be understood that the coating or plating may be of other metals which as compared with steel are relatively soft and have the same adhesive characteristics, 70 among which may be mentioned copper, nickel and tin which in common with silver are not subject to corrosion and therefore are not affected by moisture to which a strop in ordinary practice is constantly exposed. 75

An attaching plate 18, which is detachably secured to the strop by means of bolts and winged nuts 16, is connected to the hanger 14 by means of a swivel 15, the swivel permitting the strop to return readily 80 so as to give access with equal facility to both sides or surface thereof. The hanger 14 is of hollow formation and open at one end. This end is closed by a plate 17 which has threaded engagement with the hanger 85 and to which the swivel 15 is removably connected by a bolt 15^a. The other end of wall 17^a of the hanger 14 is provided with an opening 17^b to permit the hanger to be engaged with a hook 17^c secured to a wall 90 or other support. An attaching plate 19 provides means for connecting the handle 13 to the strop. This plate is secured to the handle 13 by rivets 20 and it is detachably secured to the strop by bolts and wing nuts 95 21. The handle 13 is hollow and open at one end to form a receptacle for the rolled strop blade, as shown in Figures 5 and 6 of the drawing. The hanger 14 is adapted to receive the handle 13 carrying the rolled blade, 100 the swivel 15 and the attaching plate 18, as shown in Figure 5 of the drawing, the end wall 17 forming a closure to retain the parts 13, 15 and 18 within the hanger.

The parts of the razor strop may be readily and quickly detached and placed within 105

the hanger 14. The hanger 14 containing the other parts of the razor strop forms a small package which may be placed in a valise, suitcase or trunk for storage and transportation.

Having thus described the invention, what I claim is:—

1. A razor strop having a flexible body of steel provided with a coating or plating of relatively soft metal.
2. A razor strop having a body of flexible steel provided with a coating or plating of silver.
3. A razor strop having a body of flexible steel provided with a coating or plating of

relatively soft metal and scored or roughened on one side.

4. A razor strop having a body of flexible metal provided with a coating of relatively softer metal.

5. A razor strop having a body of rollable material and a hollow handle member detachably secured to said body and adapted to receive said body when rolled.

In testimony whereof I affix my signature in presence of two witnesses.

WILLIAM W. GRAVES.

Witnesses:

J. IRA L. GRAVES,
EVERETT H. WALDRON.
